DESCRIPTIVE FOLDER

Robert M. Campbell, Beaumont, Tex.

Application March 24, 1931; Serial No. 524,823

7 Claims. (Cl. 35—12)

The invention relates to an improvement in descriptive folders wherein a moral is described which includes the releasing of an obligation by means of removing an entangling cord or string.

5 It is one of the objects of the invention to provide a descriptive folder wherein the various pages depict the steps in the releasing of an obligation and in which the pages are bound together by a string or cord which is entwined about them and which is adapted to be released at the end of the description.

Another object of the invention is to provide a descriptive booklet in which each of the pages is shown as illustrating one step in a lesson story 15 and in which the pages or sheets are bound together as an illustration of how the lesson taught by the descriptive lesson may be entwined about the subject matter illustrated on the pages.

Another object of the invention is to provide a descriptive booklet illustrating the various phases 20 in the development of the subject matter which phases are entwined by a flexible element which is arranged to be released at the completion of the description.

25 Other and further objects of the invention will be readily apparent when the following description is considered in connection with the accompanying drawing wherein

Fig. 1 is a view looking down on the top edge 30 of one form of the descriptive folder and showing the sheets thereof spaced apart to illustrate the connecting or entwining cord.

Figs. 2 to 7, inclusive, show the arrangement of the string as passing through the sheets of the 35 folder and illustrating the string as being entwined about the particular subject matter which is illustrated on the pages.

The invention may best be understood by having reference to Fig. 1 wherein 2 may represent the front cover and 3 the back cover of a folder. 40 These covers may be attached together in any desired manner such as by binding, or ring clips, or clamps of any description. For purpose of illustration, however, spring rings 4 have been shown as holding the parts together. These rings are also arranged to retain in position the flyleaf 5 and the sheets 6, 7, 8, 9, 10 and 11, as well as the rear flyleaf 12. It is to be understood that any desired number of sheets may be 45 provided in order to illustrate the various steps of the lesson which is to be described. Fig. 2 shows the back side of the flyleaf 5 and the front page 13 of the sheet 6. This page 13 illustrates a residence and it is intended to portray the idea 50 of this residence having been purchased by the

head of the family while he was alive. However, he was unable to make the entire payment for the home and it was necessary to take a mortgage upon the home. This mortgage is suggested by means of the string or cord 14, which is shown as arranged in two strands which pass about the house illustrated. These strands pass through the sheet 6 by means of the openings 15 and it is intended to convey the idea that the home is tied up with the mortgage strings or that the mortgage holder is primarily the owner of the home. The back page of sheet 6 is shown at 17 and contains a photograph 18 or other illustration depicting the pleasant circumstances under which the family were enjoying their new home 15 which had been illustrated on the previous page. These circumstances, however, like the home on the preceding page, are tied up or entangled by the strings 14 which have been passed through the openings 15 in the sheet. The strings 14 20 continue and may be entwined about each other in any desired manner so that they extend across to the front page of sheet 7 and pass therethrough in a manner similar to that in which they have been passed through the sheet 6.

25 Another view showing any desired circumstances may be attached to this page 19 and the illustrative wording on the page is intended to convey the idea that they are mailing a check every month to meet the obligation with respect 30 to the mortgage which has been taken on the home. It should be noted that when the pages are in the position shown in Fig. 1 the strings are positioned loosely between the pages. However, when the pages are shown in the position 35 such as Fig. 3, etc. the strings are then drawn tightly across between the pages so that when the folder is being displayed the strings have the appearance of being drawn tightly about the subject matter illustrated. This is particularly 40 true of sheets 7 and 8, as seen in Fig. 4, and the wording on page 20 of sheet 7 is intended to convey the idea of the death of the head of the family, or the person insured, or the person who is carrying the burden of the obligation of paying 45 for the enjoyment which has been shown on the preceding pages. The string 14 is shown as having been drawn tightly across the page and about the illustration which may appear in the space 50 21. The front page 22 of sheet 8 may contain 50 an additional illustration showing the difficulty in which the family may be involved, illustrated by the tombstone illustrated. The strings 14 are so arranged that they will be drawn particularly tight across these pages 7 and 8. Page 23 55

of sheet 8 may contain an illustration of the difficulties of the survivors of the deceased and as here shown contain wording to the effect that they are being evicted from their home which is illustrated on the first page. The front page 24 of sheet 9 contains additional information on any subject desired and the strings 14 pass through both sheets 8 and 9 as previously described.

Page 25 of sheet 9 may contain a miniature form of a mortgage insurance policy which the deceased could have obtained in order to have provided for the obligations which he incurred during his life and in the particular illustration a mortgage protector policy has been illustrated which would have been of such amount that the mortgage would have been liquidated by the policy. The strings 14 continue through this sheet and are shown as converging on the front page 26 of sheet 10. The lesson of this story approaches its climax on this page where a means 21 of severing the strings 14 has been illustrated. Beneath these scissors or other means lies a check 28, which the survivors would receive as a result of the policy contained on the preceding page. The check is illustrated as being released by severing the strings 14 so that the entire obligation shown on the preceding pages will be released upon release of the check, and the strings 14 are shown as passing through sheet 10, as best seen in Fig. 7, where they extend from the rear page 30 thereof and pass through the openings 31 in sheet 11. The cutting element 21 suggests the release of the strings 14 so that upon removal of the check 28 the portions 14' of the string 14 are withdrawn from the openings 31 and the ends thereof are shown at 32 as having moved away from the home shown on the front page 34 of sheet 11. Complete removal of the check 28 withdraws the strings 14 from the openings 35 suggesting that the home on page 34 is completely released from the obligation. On page 26 a receipt or bank deposit slip is shown at 36 as being carried by the check and the strings 14 are shown in dotted lines as passing through the back of the check 28, the string, as attached to back, being invisible on this page.

The present folder is very impressive in its demonstration to a client due to the provision of the strings therein and the effect obtained by turning the pages so that the string is drawn tightly about the illustrations which carry the story being conveyed to the client. It is to be understood that this string may be passed through the pages and arranged about the illustrations in any desired manner but the invention is intended broadly to include the idea of entwining a string about the illustrations on the pages. While the invention has been shown and described as illustrating the burden caused by a mortgage, it is to be understood that it can be used to illustrate other kinds of subject matter. In the further development of the invention it is intended that the illustrations may be altered as desired according to the particular message which is to be conveyed by the descriptive folder.

In order that the book or folder may be used repeatedly the severing element 21 may be permanently fixed to the front of sheet 10 with the strings 14 passing between the blades thereof, and also through the openings 15 in the page. They may end directly beyond the page and a separate piece of string such as 14' may be provided which passes through the check 28, the openings 35 in the sheet 10 and the openings 31 in sheet 11, so that they will be entwined about

the subject matter shown on page 34. The ends of this string 14' may remain loosely on the back side of sheet 11 as best seen in Fig. 1.

In this manner when the folder is being used the demonstrator need only grasp the end of the check 28 and pull it from beneath the cutting element 21 so that the string 14' is drawn entirely away from the subject matter shown on page 34. This materially improves the operation and manipulation of the folder as the string 14' then can be replaced in the openings 35 and 31 with ease and the same impression has been conveyed to the client.

On page 20 a separate piece of string such as 38 may pass about the illustration 21 and be fastened thereto so that it gives the impression that the strings 14 have been passed about the illustration, whereas in reality they merely pass through the page.

It is intended in the further development of the invention that various lessons can be described on the pages of the folder in such a manner that the entwining string or cord will serve to illustrate how the problem may be tied up or entwined by other circumstances or obligations and the various pages may illustrate subject matter which is appropriate to the particular lesson which is to be conveyed to the client.

Having thus described my invention, what I claim as new is:

1. A descriptive lesson folder, including a plurality of attached sheets, a picture of economic subject matter on said sheets, a flexible means to suggest economic obligations entwined through and about said sheets whereby turning of said sheets in one direction tends to tighten said flexible means and turning in another direction tends to loosen said flexible means whereby the making and releasing respectively of the economic obligations is suggested by said flexible means.

2. A descriptive booklet including sheets carrying descriptive subject matter illustrative of an economic problem, a cord entwined with said sheets in a manner which suggests the complications in which the problem is involved, and means to release said cord as an indication of the release of the problem of the complications.

3. A folder including a plurality of pages, having a descriptive story, an illustration on each side of each sheet depicting a step in the descriptive story being shown, and intertwined flexible means passing through said pages and said illustrations to suggest obligations indicated by the subject matter of the description, and means to suggest the severing of the flexible means as an indication of the release of the obligations.

4. A descriptive folder including a plurality of pages, an illustration on each page depicting a phase of the subject matter of the description being shown, and intertwined flexible means passing through said pages and said illustrations to suggest obligations indicated by the description, means to sever the flexible means as an indication of the release of the obligations, and additional means to withdraw the severed portion from its intertwining position.

5. A descriptive folder including a plurality of sheets, a display of descriptive matter on said sheets and a flexible cord slidably passing through said sheets and illustrative upon turning of the sheets of the entanglements which may arise in connection with the subject matter of the description.

6. A booklet of the character described including a plurality of sheets, illustrations on said

sheets of economic subject matter, intertwining means passing about said sheets to depict obligations in which the economic subject matter is involved, and means to sever said first means as an illustration of the release of the obligations from the subject matter.

7. A descriptive booklet adapted to convey an economic lesson including a plurality of sheets, openings through the sheets, illustrated matter

on the pages of said sheets showing the assuming of an obligation, its benefits and burdens, and means also carried by said sheets and passing through said openings to suggest how the illustrated matter is involved in obligations, and additional means to suggest the release of the first means from the illustrated matter.

ROBERT M. CAMPBELL.
